UNITED STATES PATENT OFFICE.

VICTOR R. DESPARD AND HANS C. R. POPP, OF VALPARAISO, INDIANA, ASSIGNORS TO
MCGILL MANUFACTURING COMPANY, OF VALPARAISO, INDIANA, A CORPORATION
OF INDIANA.

ELECTRIC CLUSTER LAMP BODY AND SHADE HOLDER.

Application filed June 3, 1927. Serial No. 196,262.

Our invention relates to means for securing the hollow body of an electric lamp cluster together and for securing the shade such as is commonly used upon floor and table lamps to the cluster.

It is a purpose of this invention to provide securing means of this character which, when placed in position will firmly secure the hollow body which is normally formed of two semi-spherical portions together, and which will also rigidly mount the shade thereon.

Another purpose of the invention is to provide means whereby the same securing structure can be utilized with standard fittings of different sizes without in any way interfering with the body mounting and with but slight change in the elements used. In the standard structures now used for securing lamp shades on clusters of this character, two sizes are principally applied and heretofore it has been necessary where a cluster is equipped with the securing means of one size to remove the securing means and utilize a different one in order to use the standard parts of the other size. With our invention, a standard smaller size may readily be changed to accommodate the larger size by the simple addition of two elements which fit in with the other standard securing means used with the smaller size.

Other objects and advantages of the invention will appear as the description proceeds when taken in connection with the accompanying drawings. However, we wish it to be understood that we do not intend to limit ourselves to the exact details shown and described, but that we intend to avail ourselves of all such modifications as would occur to one skilled in this art and as would fall within the scope of the claims.

In the drawings:

Fig. 1 is a side view partly in section illustrating the invention;

Fig. 2 is a sectional view showing the mounting means as utilizing the standard small size shade mounting; and

Fig. 3 is a front view of the supporting member upon which the shade rests.

Referring now in detail to the drawings, the numeral 5 indicates the stem or standard which supports the hollow body 6 constructed in this case of the lower portion 7 and the upper portion 8 and having a pair of lamp

sockets 9 and 10 secured thereto, this construction being similar to that shown in our co-pending application Serial No. 197,944 filed June 10, 1927, upon electric light cluster.

As shown, the upper portion of the hollow body is provided at its junction with the lower portion with the outwardly and downwardly extending flange 11 which fits over the top of the lower portion 7. Rigidly supported within the hollow body as shown by our co-pending application, is the member 12 which has the horizontal portion 13 upon which the upper half 8 of the hollow body rests. This hollow body as shown, is depressed as at 14 and provided with an opening through which the screw-threaded stem 15 in the portion 13 of the member 12 extends.

In order to clamp the hollow body down upon the member 13, we provide the member 16 which has screw-threads engaging the stem 15 whereby it may be screwed down to clamp the portion 14 of the hollow body 8 between it and the portion 13 of the member 12. This member 16 as shown more clearly in Fig. 2 has an external shoulder at 17 for receiving the finishing tubular member 18 thereon. The member 16 is also provided with an enlarged opening at 19 extending downwardly throughout the greater portion of its length and screw-threaded for a purpose which will presently appear.

Now in using the standard small size fixtures and finishing top member for securing the lamp shade, we provide the flat disk 20 which is screw-threaded to receive the member 15 so that it may be threaded down to rest on the tube 18. In order to make a firm support for this member, we also depress it as at 21 so as to fit inside the tube 18 and prevent lateral movement between the stem 15 and the tube 18. The member 20 being provided with the flat portion on top forms a good support for the lamp shade which is secured in place by means of the finishing nut 22 screw-threaded to receive the top of the member 15.

Now if it is desired to change to the large standard size, the finishing cap member 20 is removed together with the cap 22, and the tubular member 23 is screw-threaded into the hollow portion 19 of the member 16, the member 23 being tubular so that it will read-

ily receive the member 15 and being screw-threaded throughout its length serves also to receive the supporting member 24 which is provided with a screw-threaded opening to fit the member 23. The shape of the member 24 is substantially the same as that of the member 20 and it is also provided with a shoulder as at 25 for preventing any lateral movement between the member 23 and the sleeve 18. The lamp shade 26 may then be placed upon the member 24 and secured thereon by means of the large finishing nut 27 to complete the structure of the lamp. Thus, it will be seen that by the insertion of the member 23 the large finishing members such as 24 and 27 which are the larger standard size may be applied directly to the securing means of the hollow body fitted with the stem 15 to receive the smaller standard size fittings and in this way considerable replacement is avoided since it is not necessary to at all disturb the hollow body and the means for securing the parts thereof together.

From the above description it is thought that the construction and the advantages of this device will be clear to those skilled in this art, and having thus described our invention, what we claim and desire to secure by Letters Patent of the United States is:

1. Lamp shade mounting means for electric light clusters comprising a screw-thread-

ed stem projecting from the cluster body, a clamping member screw-threaded thereon and having an enlarged recess extending downwardly from the top thereof, a sleeve on said member projecting thereabove, a tubular member detachably mounted in said recess and surrounding said stem, a disk member resting on said sleeve and screw-threaded on said tubular member, and a securing member screw-threaded on said tubular member above said disk for clamping a lamp shade thereon.

2. Lamp shade mounting means for electric light clusters comprising a screw-threaded stem projecting from the cluster body, a clamping member screw-threaded thereon and having an enlarged recess extending downwardly from the top thereof, a sleeve on said member projecting thereabove, a tubular member detachably mounted in said recess and surrounding said stem, a disk member resting on said sleeve and screw-threaded on said tubular member, and a securing member screw-threaded on said tubular member above said disk for clamping a lamp shade thereon, said disk having means thereon preventing lateral movement between said sleeve and said tubular member.

In witness whereof, we hereunto subscribe our names this 16th day of May, A. D. 1927.

VICTOR R. DESPARD.
HANS C. R. POPP.
